CATHODE ASSEMBLY FOR ELECTRIC
DISCHARGE TUBES

Henricus Johannes de Weyer, Eindhoven, Netherlands, assignor to Hartford National Bank and Trust Company, Hartford, Conn., as trustee

Application December 6, 1947, Serial No. 790,105.
In the Netherlands November 13, 1946

Section 1, Public Law 690, August 8, 1946
Patent expires November 13, 1966

4 Claims. (Cl. 250—27.5)

1

This invention relates to an electric discharge tube comprising an indirectly heated cathode which is formed by swaging and, drawing or rolling a tubular conductor containing one or more conductors with the interposition of powdered insulating material, the cathode being flattened over at least part of its length. Such a cathode, moreover, is adapted to be curved into any desired form. Owing to the compact construction and the small diameter of such a cathode its operation requires very little thermal energy. However, comparatively great heat losses may yet occur at the points of supporting and fastening the cathode, for example where it engages a tension spring or a supply conductor or where separate members are secured to it to fasten it in a centring member.

It has now been found that special advantages are obtained if the cathode is flattened at definite points. Thus, for example, the thermal losses are materially reduced if in an electric discharge tube comprising an indirectly heated cathode formed by swaging and drawing or rolling a tubular conductor containing one or more conductors with the interposition of powdered insulating material, which cathode is one or several times bent and, at least over part of its length, flattened, inactive cathode parts are flattened, according to the invention, at the points of support in such manner that the cathode engages the supporting members only with a narrow edge. This yields the advantage that not only less heat is dissipated but consequently also the temperature distribution becomes more even throughout the length of the cathode. Moreover, the cathode becomes rigid, i. e. that it does not tend to alter its shape spontaneously. In addition, such a cathode is adapted to be supported in a very simple manner in insulating centring members.

If such a cathode is one or more times bent into the shape of a hair-pin or in zigzag fashion, it may be flattened at the bends and at the ends. This flattening of the bends is preferably effected in a direction at right angles to the plane of the bend, so that the bend becomes rigid, whilst the heat transference to a supporting member engaging the bend, for example a tension spring, may be low, since the flattened bend of the cathode rests with a narrow edge on such a supporting member. Since the bend is rigid such a supporting member may, moreover, be very narrow. The flattened curved parts may be slipped through a narrow slit in a centring member and hooked to a supporting member.

The flattened parts near the ends of the cath-

2

ode serve to fasten the cathode ends in a centring member, these flattened parts being, for example, introduced into an aperture having a narrow slit in such manner as to extend at right angles to the longitudinal direction of the slit and prevent the cathode ends from being drawn through the slit. In this case it is consequently not necessary to secure cross-bars or supporting wires to the cathode ends, so that the dissipation of heat will be small. Moreover, the flattened parts at the ends of the cathode rest with a narrow edge on the centring member, for example, a mica disc, so that only little heat is dissipated. In accordance with the shape of the aperture in the centring member the ends may be flattened in the same plane as the bends or at right angles thereto.

It has been found that a cathode according to the invention exhibits a very uniform temperature distribution throughout its active length.

In order that the invention may be more clearly understood and readily carried into effect, it will now be described more fully with reference to the accompanying drawing, in which:

25 Figure 1 is a front view of a cathode assembly according to the invention.

Fig. 2 is a side view of the cathode assembly.

Fig. 3 is a sectional view taken along line 3—3 of Fig. 1, and

30 Fig. 4 is a transverse sectional view on an enlarged scale of the cathode shown in Fig. 1.

In the drawing the reference numeral 1 designates the cathode which in the present case is bent into the shape of a hair-pin and supported by means of the centring members 2 and 3. As shown in Fig. 4 cathode 1 comprises a central filament 6 surrounded by tubular outer conductor 10, the intervening space being filled with a powdered insulating material 11. At about 0.5 mm. from its ends the cathode 1 is provided with flattened parts 4 which extend at right angles to the plane of the hair-pin and prevent the ends from being drawn through the apertures 7, 8 of the centring member 2 consisting, for example,

45 of mica. To this end these apertures exhibit preferably a wide part 7 for the introduction of the flattened cathode end 4 and a narrow part 8 into which the round part of the cathode can just be slipped but through which the flattened part 4 cannot pass. The narrow part 8 may either exhibit the form of a slit to which the plane of the flattened part 4 extends at right angles, or be formed in a known manner by superposition of two insulating members in such manner that the cathode end is locked in a small

55

aperture. The curved part 5 is likewise flattened, at least partly, but in this case in the plane of the bend, slipped through a slit 8 of the member 3 and hooked to the tension spring 9. The cathode is heated by means of the filament 6 and is adapted to be flattened in a very simple manner by impact or pressure with the aid of a stamp. For this purpose the cathode is bent on a jig and flattened at the desired points. Thus the cathode becomes rigid, i. e. that it no longer tends to alter its shape after removal of the jig. This is promoted by the fact that the curved parts are flattened in the plane of the hair-pin as shown in the drawing. The supply to the cathode body is preferably effected at a point of suspension in a bend.

It is obvious that the cathode may consist of a plurality of parts which are bent to and fro one or several times, for example hair-pin shaped parts which may extend in one plane or in a cylindrical plane. Instead of being hair-pin shaped, the cathode may also be V- or U-shaped, staggered or bent in any convenient way.

What I claim is:

1. A cathode assembly for an electric discharge tube, comprising a supporting member and an indirectly heated cathode member having an inner conductor, and outer conductor spacedly surrounding said inner conductor and powdered insulating material separating and compactly filling the space between the inner and outer conductors, said outer conductor comprising a first tubular portion and a second flattened portion having a narrow edge, said second portion engaging said supporting member with the said narrow edge thereof.

2. A cathode assembly for an electric discharge tube, comprising a supporting member and an indirectly heated cathode member having a bent portion and a straight portion and comprising an inner conductor, an outer conductor spacedly surrounding said inner conductor and powdered insulating material separating and compactly filling the space between the inner and outer conductors, the outer conductor at said bent portion being flattened in the plane of the bend and having a narrow edge and at said straight por-

tion being tubular, said bent portion engaging said supporting member at said narrow edge.

3. A cathode assembly for an electric discharge tube, comprising a supporting member and an indirectly heated cathode member having an inner conductor, an outer conductor spacedly surrounding said inner conductor and powdered insulating material separating and compactly filling the space between the inner and outer conductors, said outer conductor comprising a first tubular portion and second flattened end portions each having a narrow edge, said second end portions engaging said supporting member with the said narrow edge thereof.

4. A cathode assembly for an electric discharge tube, comprising an upper insulating plate member provided with a slit, a lower insulating plate member provided with a pair of apertures and spaced from said upper insulating member, U-shaped indirectly heated cathode member having an inner conductor, an outer conductor spacedly surrounding said inner conductor and powdered insulating material separating and compactly filling the space between the inner and outer conductors, and a cathode tensioning member positioned above said upper insulating member, said outer conductor comprising tubular portions intermediate the bent and end portions of the said cathode and flattened portions at said bent and end portions each provided with a narrow edge, said end portions engaging said lower insulating member with the narrow edge thereof and said bent portion being positioned within said slit and engaging said tensioning member with the narrow edge thereof.
